WINDOW CONSTRUCTION

William Marcus, Cleveland, Ohio

Application January 9, 1948, Serial No. 1,303

1 Claim. (Cl. 20—51)

1

This invention relates to improvements in window construction and more particularly to an arrangement of a double hung window so that the sash may be run up and down in the normal manner, but the entire window may be swung into the room for cleaning after the manner of a casement window.

This application is a continuation in part of my copending application Serial Number 725,190, filed January 30, 1947 for "Window Construction," and which has now been abandoned.

One of the objects of the present invention is to provide a window of the type described above where substantially all of the window opening is available for glass portions of the window whereas prior constructions directed to this problem have closed a considerable portion of the window opening with heavy frame constructions.

Another object of the present invention is to provide a double hung window adapted to be opened into the room as a unit where the only portions of the frame swinging with the window are slide guides, one for each side of the window.

Another object of the present invention is to connect two sliding sashes and two slide guides in a novel manner so that the entire unit may be swung into the building for cleaning.

Another object of the present invention is to provide novel means for holding a sliding sash in different positions as it is moved up and down, this holding arrangement being peculiarly adapted to window construction of the type described adapted to be swung inside a room for cleaning.

Another object of the present invention is the provision of window construction as described above adapted for use with Venetian blinds and so arranged as to protect the Venetian blinds when the entire window is swung into the room after the manner of a casement window.

Another object of the invention is the provision of means for swinging a sash into a room for cleaning wherein the sash has a horizontally interlocking and vertically slidable connection with a vertical guide which is hinged to the window frame on one side of the sash, while at the other side, another vertical sash guide is mounted in the frame for lateral movement toward and away from the sash. It results from this construction that when one of the side guides is moved out of engagement with the sash, the sash is swingable about the hinged guide into the room for cleaning and maintenance.

Still another object of the present invention is the provision of a vertically movable sash having horizontally interlocking and vertically slidable connections with a guide which in turn

2

is hinged to the frame. This hinge connection comprises slidable parts permitting the movement of the sash and guide toward the room before the sash and guide are swung about the hinge connection into the room for cleaning and maintenance. This permits the use of my invention in those locations where there is considerable depth in the window frame between the inner wall of the room and the sash. Other advantages follow as will later appear in connection with the specification and drawings.

Other objects and advantages of the present invention will be apparent from the accompanying drawings and specifications and the essential features thereof will be set forth in the appended claim.

In the drawings,

Fig. 1 is front elevational view taken from inside a building showing my improved window in closed position;

Fig. 2 is a similar view showing the upper and lower sashes moved respectively downward and upward a small amount and locked in position ready to be swung into the room for cleaning;

Fig. 3 is an enlarged sectional view taken along the line 3—3 of Fig. 2 and showing in dot-dash lines how the window may be swung about its hinges;

Fig. 4 is a fragmental sectional view taken along the line 4—4 of Fig. 3;

Fig. 5 is a sectional view taken along the line 5—5 of Fig. 6, the position of this view also being shown by the line 5—5 of Fig. 2;

Fig. 6 is a fragmental view taken along the line 6—6 of Fig. 5;

Fig. 7 is a fragmental sectional view enlarged of the right-hand portion of Fig. 3 showing the parts as the window starts to swing into the room;

Fig. 8 is a front elevational view of a modified form of my window construction, this view being taken from inside a building showing the sash in a closed position;

Fig. 9 is a similar view showing the upper and lower sashes of Fig. 8 moved to the proper position for swinging the entire window into the room for cleaning;

Fig. 10 is an enlarged fragmental sectional view taken along the line 10—10 of Fig. 9;

Fig. 11 is a sectional view enlarged taken along the line 11—11 of Fig. 10;

Fig. 12 is a front elevational view of a window equipped with a modified form of my device, certain parts being broken away to more clearly show the construction;

Fig. 13 is a sectional view enlarged taken along

the line 13—13 of Fig. 12 with portions of the sashes broken away to more clearly show the construction;

Figs. 14 and 15 are enlarged fragmental sectional views taken along similarly numbered lines of Fig. 12; while

Fig. 16 is a fragmental perspective view of a vertical side edge of one of the sashes of Figs. 12 to 15 showing a form of sash balance which is used therein and omitting certain corner angles of the sash to more clearly show the construction.

Fig. 17 is a front elevational view of another modification of my window construction. Fig. 18 is an enlarged fragmental sectional view taken along the line 18—18 of Fig. 17 with the swinging movement of the sashes indicated in dot-dash lines;

Fig. 19 is a fragmental sectional view taken along the line 19—19 of Fig. 18. Fig. 20 is a perspective view of the hinge and bracket shown in section in Figs. 18 and 19. Fig. 21 is an enlarged fragmental sectional view taken along the line 21—21 of Fig. 17; while

Fig. 22 is a view similar to Fig. 21 showing the position of the parts necessary to swing the sashes into the room.

The double hung sash window is a very popular type, but has the known disadvantage that it is difficult to clean without going outside the building. Many structures have been suggested to cure this difficulty but, to the best of my knowledge, they have been unsuited to the purpose either because they were too complicated or because they used heavy framework which occupied much of the window opening, thus cutting down the available glass area. My invention avoids both of these difficulties by providing parallel slide guides 10 and 11 along opposite sides of the window. The lower sash 12 and the upper sash 13 have their vertical sides dovetailed into the guides 10 and 11, as clearly shown in Fig. 3. Thus, the members 10, 11, 12 and 13 are tied together in a horizontal direction. The guide 10 is mounted by hinges 14 on the frame 15 which is a fixed portion of the building. The guide 11, when the window is closed, is locked to the frame 15 by means of locking bolts 16 which are manipulated by means of a vertical rod 17 slidably mounted on the guide 11. When the bolts are in their uppermost position, as shown in Fig. 2, they enter into notched openings 18 in the casement frame. They then slide downwardly into pockets 19 arranged to retain the bolts. In this closed position of the window the upper and lower sashes move freely up and down in the guides 10 and 11 in the manner of a double hung sash window.

When it is desired to open the window into the room for the purpose of cleaning the outer face of the glass the lower sash is moved upward slightly from the position of Fig. 1 (where the lower edge is indicated at 12a) to the position of Fig. 2 where the lower edge 12a will clear the window sill 20. At the same time, the upper sash 13 is moved downwardly from the position of Fig. 1 (where the upper edge is indicated at 13a) to the position of Fig. 2 where the edge 13a clears the portion 15a of the casement frame. In this position of the parts, the sashes 12 and 13 are locked to each other and to the guides 10 and 11 against relative vertical movement. Any suitable locking means may be utilized for this purpose. In Figs. 1, 2 and 3, I have shown lock bolts 21 on opposite sides of the window, each bolt

being slidably mounted by a pin and slot construction 22 upon a base plate 23 which is secured to the lower sash. Each bolt has a locking nose 21a which enters into a suitable notch in the side guide 10 or 11. Each bolt also has a locking nose 21b which enters into a notch 13b in the frame of the upper sash. Obviously, when these bolts are in the position shown in Fig. 3, the lower sash 12 cannot move up and down because of the engagement of the locking noses 21a in the guides 10 and 11. Also, the sash 13 cannot move relative to the other parts because of the engagement of the locking noses 21b in the notches 13b. It will be noted in Fig. 2 that the vertical rod 17 has been moved upwardly from the position shown in Fig. 1 so that the bolts 16 are in registration with the notches 18. The window is now in position to be swung into the room about the hinges 14 and such movement is indicated in the dot-dash lines of Fig. 3.

Preferably, I provide means for insuring proper positioning of the sash and guide unit when the window is closed. For this purpose, near the upper portion of the guide 11 I have struck outwardly a tongue 24 from each of the flat guide faces 11a. In the casement frame I have secured two brackets 25, each of which has a projection 25a upon which one of the tongues 24 is adapted to rest. There may be a slight incline on the tongue or the projection 25a so that the parts will enter into the proper position easily. Referring to Fig. 7, it will be noted that these parts are so arranged that as the corner 26 of the guide 11 moves away from the stop 27 along the path of the dot-dash line 28 it will clear the projection 25a.

Preferably, means is provided for sealing the guides 10 and 11 against air leakage. The means here shown comprises strips 29 and 30 in the guides 10 and 11 respectively, each strip running the full length of the window. These strips are readily held in the dovetail pockets 31 and 32 which are provided in the guides between the sash-receiving dovetails. These sealing strips 29 and 30 engage the casement frame 15 when the window is closed.

Preferably, a flange 11b (Fig. 3) is provided along the entire length of the guide 11 on the inside face thereof extending away from the window and engaging a shoulder 15b in the casement frame. This closes the crack extending in a vertical direction which is necessarily provided for the swinging movement of the window.

It should be understood by those skilled in this art that a very acceptable window might be provided wherein one of the sashes, for instance the upper sash 13, might be fixed in the guides 10 and 11 leaving only the lower sash 12 slidable. In such a case, the portion of the guides holding the upper pane of glass might be simplified over the construction shown but such modification will readily occur to those skilled in this art and need not be further described here.

In Figs. 5 and 6, I have shown a novel means for holding one of the sliding sashes in approximately any position to which it is raised. This means is shown in detail in Figs. 5 and 6, as the same would be applied to the lower left-hand portion of the sash 12, as indicated in dotted lines in Fig. 2. The same structure might be applied to the upper sash, as is indicated in dotted lines in the upper left-hand corner of the sash 13 in Fig. 2.

In Figs. 5 and 6, I have shown a bracket 33 secured in a chamber opening 34 of the sash 12.

This bracket has downturned end pieces 33a in which a shaft 35 is rotatably mounted. The outer end of this shaft carries a gear 36 beveled to conform to a wall 10a of the guide 10. Arranged vertically in this wall I have punched openings 10b providing a rack to coat with the teeth of the gear 36 as the window sash is moved up and down. A helical compression spring 37 surrounds shaft 35 and is confined between one of the bracket ends 33a and a follower 38 which has an opening whereby it rides on the shaft. The follower has a projection 38a which rides in a sinuous groove 39 extending around the shaft 35. It results from this construction that as the sash 12 is moved up and down the gear 36 travels along the fixed rack 10b so as to rotate shaft 35. The groove 39 causes the follower 38 to move from its position farther toward the left, as viewed in Fig. 6 to a position farther toward the right when that portion of the groove 39 comes around. As the follower 38 moves toward the right, as viewed in Figs. 5 and 6, it compresses spring 37. When the operator releases the sash 12, the follower will move along the groove 39 to the nearest position corresponding to that shown in Fig. 6. At this point, the sash will remain stationary because the parts are so constructed and arranged that the weight of the sash acting to turn the shaft 35 is ineffective to cause the projection 38a to travel along the groove 39 in a direction to compress spring 37. The friction resisting this movement of the projection 38a along the groove 39 is too great, and the sash remains in the position to which it has been raised.

In the modification shown in Figs. 8 to 11 inclusive, I have provided means to protect Venetian blinds in case they are used. Here the casement opening is shown at 40 and mounted in the upper portion thereof is a bracket 41 from which hangs the Venetian blind 42 in the customary manner. In this form of my device the lower sash 43 and the upper sash 44 are provided with dovetailed edges which are vertically slideable in the parallel slide guides 10' and 11' which are exactly like those shown at 10 and 11 in the first described form except that they are cut off at the point 45 for the purpose of protecting the Venetian blinds. A slide portion 10" is directly aligned above the member 10' and a portion 11" is vertically aligned above the slide guide 11'. As clearly shown in Fig. 11, the slide guide portions 10" and 11" are fixed to the casement 40 by means of screws 46. Suitable spacing members 47 and 48 are supplied between the guides 10" and 11" and the casement 40 where necessary to maintain proper vertical alignment. The usual bayonet lock 48' is provided to lock the upper and lower sashes together when both sashes are closed. Sliding bolts 49 are secured to the lower sash 43 and adapted to extend into suitable slots 49a in the central portion of the slide guides 10' and 11' as illustrated in Fig. 10 when the lower sash is raised slightly as shown in Fig. 9. A locking member 50 is pivotally mounted at 51 on the slide guide 11' and adapted to swing to unlocked position as shown in Fig. 9 or to locked position as shown in Fig. 8 where the locking member 50a engages in a pocket 52 in the casement 40.

Preferably, the upper edges of both sashes are beveled as indicated in Fig. 11 at 43a and 44a for a purpose later described.

Holding devices are indicated for the lower sash at 53 and for the upper sash at 54. These are

like the holding members described in connection with Figs. 5 and 6 and are provided for the same purpose.

The operation of this modified form of my device should now be apparent. When the parts are in the position of Fig. 8 the slide guides 10' and 11' are in fixed position relative to the casement 40 due to the lock 50 and the inter-relationship between the sashes and the slide guides. 10 When it is desired to swing the entire window into the room for cleaning it is necessary to raise the lower sash slightly as shown in Fig. 9 and to engage the slide bolts 49 into the slots 49a. It is also necessary to lower the upper sash to the position shown in Fig. 9 so that the upper portion of this sash will clear the fixed slide guide portions 10" and 11". If the Venetian blind 42 is in its usual raised position, then the position of the upper sash as shown in Fig. 9 will clear this blind. The latch 50a is then swung to unlocked position as shown in Fig. 9 and the upper and lower sashes together with the slide guides 10' and 11' may be swung into the room about the hinges 55. The upper sash 44 may then be moved 25 relative to the lower sash 43 if desired during the washing process. During this manipulation of the sash it may be held in various positions by suitable means not shown and forming no part of the present invention. When the cleaning operation is completed the parts are swung back to the position of Fig. 9, the latch portion 50a is again engaged in the pocket 52 and the bolts 49 are withdrawn to the position of Fig. 8. Both of the sashes may now be manipulated up and 30 down in the usual manner and the movement of either sash from the slide guides 10' and 11' upwardly into the fixed portions 10" and 11" respectively is facilitated by the beveled edges 43a and 44a on the lower and upper sashes, respectively.

It should be obvious from this description that it is impossible to swing the entire window into the room until the upper sash 44 is moved downwardly out of the fixed slide guide portions 10" and 11". Thus, the Venetian blinds are always protected against damage.

In Figs. 12 to 16 I have shown another modification of my device for accomplishing the same purpose as disclosed in Figs. 8 to 11 inclusive. 50 Here a fixed frame 56 is provided as in the previous form of my device and two parallel side guides 57 and 58 extend along the vertical parallel sides of the frame 56. The guides 57 and 58 are the same except for minor details of attachment and therefore one only will be described. In Figs. 13, 14 and 15 it will be noted that each of the guides provides a pair of channel form members 59 for the upper sash and 60 for the lower sash joined together by a central web 61. The channel 59 for instance has a central web portion 59a and edge flanges 59b which are so spaced as to slidably receive the upper sash 62. To the mid portion of 59a of the channel 59 is secured a stiff metallic strip 59c extending generally parallel to the web 59a and stopping short of the flanges 59b to form free edges 59d. L-shape angular members 64 are secured to the vertically extending corners of sash 62 a portion of one of these angular members being shown in perspective in Fig. 16. These angular members 64 embrace the free edges 59d of the strip 59c so that the sash 62 is interlocked horizontally with the guide channel portion 59 but is vertically slideable 65 therein. The lower sash 63 is similarly supported

and connected in the guide channel portion 60 by means of the angular corner members 64.

As in the form of my invention shown in Figs. 8 to 11 inclusive, I here provide means for compelling the lowering of the sash 62 to a point beneath the lower edge of the Venetian blinds 65 before the window can be swung into the room. To this end, the uppermost portion of each side guide as indicated at 57a and 58a is fixed to the casement 56. The intermediate portions 57 and 58 of the side guides are adapted to be moved out of the frame 56 by the securing of the side guide portion 57 to the frame 56 by means of the hinges 66. The lowermost portion of each side guide as indicated at 58c is also fixed to the frame 56, the similar portion of 57 being not marked for clearness.

Referring to Figs. 14 and 15 it will be seen that the guide portion 57a shown in Fig. 14 is similar in all respects to the fixed guide portion 57 shown in Fig. 15 except for the manner of fastening the same to the frame 56 and sealing the same against the entry of undesirable weather effects. Referring first to Fig. 15, I have here provided a resilient sealing strip 67 extending continuously from top to bottom of the guide portion 57 and held between the flanges 59b, 60b and the web 61. The strip 67 engages the frame 56 when the window is closed so as to provide a weather tight seal entirely along the guide portion 57. It should be understood that a similar sealing strip is provided at the opposite edge along the guide portion 58.

Referring now to Fig. 14, a flexible pad or sheet 68 extending the full vertical length of the guide portion 57a is inserted between the web 59a and the frame. Screws 69 secure the web 59a to the frame 56 and are so arranged that the guide portion 59 can move slightly toward and away from the frame 56. A similar resilient pad 68' is secured between the channel portion 60 and the frame 56. The edges of the sashes 62 and 63 are beveled as indicated at 62a and 63a. It results from this construction that, when the window is not swung into the room, as one of the sashes moves from the movable portion of the side guide 57 or 58 into the fixed portion 57a or 58a respectively, the resilient cushions 68 and 68' permit the side guide to move slightly to accommodate itself to the width of the sash in case the same varies slightly from standard dimensions. Referring to Fig. 13, I have indicated in dotted lines at 70 and 70' similar resilient cushions behind the fixed guide portion 58a.

Referring to Fig. 13, a fixed portion 58c of the side guide is secured to frame 56 by means of screws 71 and back of the side guide are resilient cushioning members 72 and 72' for the purpose of providing a slight movement of the fixed guide portion laterally to accommodate itself to the width of the sash. The sash 63 is indicated as beveled at 63b for the purpose of causing the entry of the sash more easily into the fixed portion 58c.

Another advantage of the resilient cushions such as 68, 68', 70, 70' and so forth, is that they provide weather sealing strips along the fixed portion of the side guides. Since the strip 67 forms a weather seal along the movable portion of the side guide, it will be seen that my entire window is weather sealed along both of the vertical side edges thereof.

Another advantage of the fixed and movable side guide portions is that it compels the operator to move the upper sash 62 below the parting

line 73 before the sashes can be swung into the room and this protects the Venetian blind against damage. At the same time it compels the raising of the lower sash 63 above the parting line 74 so as to be sure that the lower sash will clear the sill 75 before it is attempted to swing the window into the room.

The usual bayonet lock 76 and 76a is provided between the upper and lower sashes. Fixed to the upper rail of the lower sash 63 are sliding bolts 49' which enter into the side guides for the purpose of fixing the sashes in the position of Fig. 12 before the sashes and side guide portions 57 and 58 are swung out into the room. These perform the same functions as the bolts 49 previously described.

In Figs. 12 to 16 I have shown another means for counterweighting the slideable sashes. This comprises the sash balance 77 which is fully disclosed and described in the United States Patent No. 2,230,763 granted February 4, 1941 to Albert J. Rosentreter, to which reference may be made for a more complete description.

In the modification of my invention shown in Figs. 17 to 22, inclusive, two new features are shown. The first of these involves the use of a vertical guide on the side of the sash away from the hinged guide which is movable laterally relative to the frame to free the sash for swinging movement into the room. The other novel feature is the special hinge connection clearly shown in Fig. 20. It should be understood that either of these modifications may be utilized not necessarily in company with the other but either of these modifications may be utilized in connection with previously described forms of my invention.

Referring now to Fig. 17, a fixed frame 78 is provided as in previous forms of my invention. In this frame are slidably mounted an upper sash 79 and a lower sash 80. On the left-hand side of the frame 78, as viewed in Figure 17, a vertical guide is provided having an upper portion 81 which is fixed the same as in Fig. 12, and having a lower portion 82 which has a horizontally interlocking and vertically slideable connection with the upper and lower sashes, this connection being exactly the same as described in connection with Fig. 14. For each sash the vertical guide 82 supports a vertically extending plate 83 behind which are received the angle members 84 which in turn are secured to each sash. It results from this construction that each sash is vertically slideable in the guide 82 but is horizontally interlocked so that the sash cannot fall out of the guide. Sash counterbalancing members 85 are provided exactly like the member 71 shown and described in connection with Fig. 16.

On the right hand side of the frame 78, as viewed in Fig. 17, a vertical guide 86 is provided having grooves or channels 86a and 86b for slidably receiving the upper and lower sashes, respectively. Means is provided for moving this guide 86 laterally with respect to the fixed frame 78. In the present instance, this means comprises a plurality of screws 87 passing through a central portion of the guide 86 as clearly shown in Figs. 21 and 22. Each of the screws 87 is rotatably mounted but axially fixed in the guide 86 by means of plate 88 which enter into a suitable groove 89 in the screw. The free end of the screw has a threaded connection with a plate 90 which is fixed to the frame 78. It results from this construction that in the normal position of the parts as shown in Fig. 21 the guide 86 is moved

away from the frame 78 by means of the screws 87 so that it engages and holds the sashes 79 and 80 but in position to permit these sashes to be moved up and down vertically in the normal manner of a double hung window. When it is desired to swing the sashes into the room, the screws 87 are turned until the guide 86 occupies the position of Fig. 22 where the guide 86 is moved clear of the upper and lower sashes. Access may be had to the lower screw 87, as viewed in Fig. 17, by raising the lower sash a small amount.

By the use of the modification of my invention just described, the sashes 79 and 80 and the guide 82 may be swung as a unit into the room for cleaning or maintenance of the windows. The free edges of the sashes 79 and 80 need not be permanently encased in a side guide but instead the guide 86 may remain in the position shown in Fig. 22 secured to the frame 78.

The second modification mentioned above as including the hinge shown in Fig. 20 is provided for the purpose of moving the sashes as a unit toward the room before swinging the same about the vertical pivot of the hinge connection. This is desirable for the purpose of reducing the clearance necessary between the swinging edges of the sash and the fixed frame. It is also valuable in those cases where the frame is of considerable depth from the wall of the room to the sash of the window. In such cases it is desirable to move the entire window including the two sashes and the hinged guide 82 in a horizontal direction into the room until the hinge pivot has cleared the fixed frame. Then the entire unit may be swung about the hinge pivot into the room. The construction shown in Figs. 18, 19, and 20 is applied to both of the hinges 91 shown in Fig. 17. Each hinge comprises a leaf 91a which is secured to the guide 82 and a leaf 91b which is slidably mounted in a bracket 92 which is secured by flanges 92a to the frame 78. As clearly shown in Figs. 18 and 19 the bracket 92 is recessed into the frame 78 so that the outer faces of the flanges 92a are flush with the inner face of the frame 78 which meets the guide 82. It will be noted in Fig. 20 that the bracket has lips 92b which overlie the hinge leaf 91b so as to hold the same in position as it slides back and forth. Means is provided for limiting the movement of the hinge back and forth. In the present instance a pin 93 is fixed to the bracket 92 and extends through a slot 94 in the hinge leaf 91b.

It results from this improved hinge construction that when the window is to be opened, it is moved from the full line position of Fig. 18 to the dot-dash line by sliding the hinge leaf 91b in the bracket 92. Thereafter the sashes

are moved together with the vertical guide 82 about the hinge 91.

It should be clearly understood that I may use my improved hinge, as shown in Fig. 20, with the specific form of vertical guide shown in Figs. 3, 10 and 11, or with the specific form of vertical guide shown in Figs. 14 and 15.

What I claim is:

In window construction, the combination consisting solely of a fixed frame having parallel vertical sides, two parallel vertically extending guides each providing inner and outer vertical runways, two vertically movable sashes, one sash in each of said runways, said sashes having horizontally interlocking and vertically slidable connections with each of said guides, said horizontally interlocking connections being capable of endwise slidable assembly of said sash on said guides, each of said guides having an intermediate portion movable relative to said frame and having top and bottom portions fixed relative to said frame, said intermediate portions of said guides being longer than the height of one sash, and means mounting said sashes and said two movable guide portions as a unit for movement out of said frame.

WILLIAM MARCUS.
